UNITED STATES PATENT OFFICE.

WILLIAM P. LAMAR, OF ATLANTA, GEORGIA.

PASSENGER AND FREIGHT TRANSFER SYSTEM.

1,366,008.

Specification of Letters Patent. Patented Jan. 18, 1921.

Application filed July 20, 1917, Serial No. 181,835. Renewed June 25, 1920. Serial No. 391,839.

To all whom it may concern:

Be it known that I, WILLIAM P. LAMAR, a citizen of the United States, and residing at Atlanta, Fulton county, State of Georgia, have invented certain new and useful Improvements in Passenger and Freight Transfer Systems, of which the following is a specification.

This invention relates to apparatus for transferring passengers and freight to and from moving railroad trains to avoid the usual delay at stations, and to reduce the amount of rolling stock necessary to handle a given amount of traffic.

In my application Serial Number 136,496, filed December 12, 1916, I disclose an apparatus of this character in which a transfer car which may be loaded with passengers or freight, is taken from a station platform into a special reception car on a train by mechanical means, without stopping the train, and which is discharged from the reception car on to the platform at the next station.

My present invention is an improvement upon the apparatus described in my above mentioned application and has for its object to provide mechanical means for accomplishing the same result in a different manner, which, under some circumstances, may be more satisfactory than the apparatus heretofore described.

The invention will be fully disclosed in the following description, taken in connection with the accompanying drawings in which,

Figure 1 is a plan view of a station platform adjacent a railroad track, showing the general positions of the train and transfer car when the transfer is about to take place,

Fig. 2 is a side elevation of one of the cars of the train, showing portions of the special apparatus attached thereto,

Fig. 3 is an end view of the transfer car, showing also a portion of the platform,

Fig. 4 is a plan view of the reception car, the roof being removed,

Fig. 5 is a plan view of a portion of the mechanism located beneath the floor of the reception car,

Fig. 6 is a side elevation of the reception car, portions being omitted,

Fig. 7 is a section along the line 7—7 of Fig. 4,

Fig. 8 is a plan view of a detail, 55

Fig. 9 is a plan view of some of the mechanism located beneath the station platform,

Fig. 10 is an enlarged plan view of a detail,

Fig. 11 is an end view of the same, 60

Fig. 12 is an enlarged sectional view of portion of the reception car.

The platform —10— is located as close beside the railroad track —11— as possible, so that the transfer car —T— has only a 65 short distance to travel over the bridging members between the reception car and the platform. The train is preferably composed of seven cars with the reception car —R— located in the middle, the preceding and succeeding cars having mechanism attached thereto, coöperating with the mechanism of the platform and reception car in the operation of the device.

The transfer car —T— is mounted upon 75 ball bearing caster wheels —12— clearly shown in Fig. 3, which are adapted to run in parallel grooves —13— in the platform —10— and is somewhat shorter than the car —R— in the train which is adapted to 80 receive it. In the drawings I have shown the car —T— to be a flat car, but it may be inclosed if desired, in any suitable manner, to protect and secure the passengers or freight thereon.

In taking a heavy car on to a moving train and in putting it off, two mechanisms are used which act together in accomplishing this result—both of which are operated by the energy of the train, but in different 90 ways.

One mechanism is necessary to accelerate the transfer car in taking the same on to the train and to retard and stop it when it is put off, and the other is the mechanism 95 actually accomplishing the drawing into and thrusting from the reception car of the transfer car. The means for accelerating and retarding the transfer car will first be described.

Beneath the platform —10— and extending longitudinally thereof are a number, preferably four, of shafts —14— arranged end to end and having at close intervals bevel gears —15— secured thereon (see Fig. 9). 105 Each of these bevel gears —15— meshes with a bevel gear —16— secured upon a short shaft —17— extending at right angles

to the shafts —14—. Also mounted upon each of the short shafts —17— is a larger gear —18— which projects up through the platform —10—. These gears —18— are 5 adapted to mesh with a short rack —19— under the car —T— and to move the car when they themselves are rotated. The rack —19— is slightly shorter than the tangential distance between two of the gears —18— which are equally spaced, so that when the car —T— passes along the grooved platform the rack —19— can mesh with only one gear at a time. The large gears are 10 equal in size but the gears 15 and 16— vary progressively in size, as shown in Fig. 9, so that the gears —18— are all driven at different speeds, those near the center of the platform rotating very slowly and those near the ends very swiftly.

20 Each of the shafts —14— is rotated by the train as it passes the platform, by means of a shaft —19a— having a bevel gear —20— in mesh with a gear —15'— at its inner end, and the gear —21— on its outer end, outside 25 of the platform, and which is connected by a chain or belt —22— with the gear —23— mounted upon a support in such a way as to mesh with racks —25— secured beneath the cars.

30 For each of the shafts —14— there is a drive shaft —19a— the gears —20, 21, and 23— being the same size for the different shafts —19a— so that the shafts —14— will all be rotated at the same speed by the train when 35 it passes the platform. As a result of this arrangement, the car —T— standing at the middle of the platform with the rack —19— in mesh with one of the gears —18— is started very slowly in the direction in 40 which the train is traveling. When the rack —19— has passed the middle gear, it engages the next one, which is rotating slightly faster, and, after leaving this one, strikes a third which is rotating still faster, and so 45 on, until the last gear is reached, at which point the car —T— is going approximately as fast as the train. After leaving the last gear in the line, the caster wheels of the car —T— pass out of the grooved tracks 50 —13— and the car is drawn into the special reception car.

Exactly the reverse of this operation takes place when the car —T— is being put off at any station. In this case, the transfer 55 car is put on that end of the platform which the reception car first passes and is then guided over the rotating gears —18—. The first or end gear will be rotating very fast, but will retard the car —T— somewhat, 60 the second will be rotating at a less speed, and will retard it further, and so on, until the car has stopped at the middle of the platform, where it may be unloaded and made ready to be taken aboard the next 65 train.

A large number of gears —18— may be used and this is desirable so that the transfer car may be started from a state of rest and gradually accelerated until it has attained a high rate of speed without overstraining any of the gears or shafts. If it is desired to pass a station platform without landing a transfer car or taking one on to the train, the car —T— is locked within the car —R— in a manner hereinafter to be described, and the racks —25— beneath the cars of the train are lifted by means of rods —26— and levers —27— on the various cars, so that they will not engage the gears —23—.

At the ends of the platform curved grooves —28— are cut which guide the caster wheels of car —T— which are on the side away from the train, toward the transfer car, to assist the mechanism in moving 85 the car —T— into and out of the car —R—.

The reception car is of the same length as the other cars in the train, but is open on one side to permit the transfer car to be moved in and out. It is provided with three 90 transverse channel members —29— which receive the caster wheels of the car —T—. These channel members are secured together by longitudinal bars —30— so as to form a rigid frame. Each of the channels is supported at its middle point by a bracket —31— and the frame is tilted downwardly toward the open side when car —T— is being taken on or put off, and is tilted back to a horizontal position when the car —T— 100 has reached its final position within the reception car. The end portions of the channel members —29— are hinged at 33 to the main portions and have their outer ends resting with a sliding contact upon blocks 105 —34—. Pivotedly secured to these blocks —34— are extensions or bridging channels —35— which support the car —T— while it is passing from the platform to the reception car or vice versa. These bridging 110 members have at their outer ends the supporting wheels or rollers —36— which roll upon a ledge —37— on the platform —10— when the train is passing the station. Between stations, the bridging members are 115 folded in, the wheels —36— entering slots —37'— in the floor of the car, the car —T— having means thereon for operating the bridging members in this manner.

Each of the bridging members is normally held by a tension spring —38— in its extended position, as shown in Fig. 4, and is held against accidental backward movement by a spring catch —39— having a shoulder —40— thereon which engages 125 the arm —41— projecting from the side of the bridging member and prevents the return movement thereof, the stop —42— on the other side of the member —35— preventing its movement in the other direc- 130

tion. The spring catch —39— extends under the horizontal arm —41— and projects upwardly and backwardly on the outer side thereof, this inclined portion —43— being 5 adapted to coöperate with the downwardly projecting bar —44— on the transfer car —T— to release the member —35—.

This downwardly projecting bar —44— has a horizontal lower portion —45— which 10 strikes the inclined surface of the spring member —39— to depress the same and release the horizontal arm. As the horizontal portion —45— of the bar —44— which is secured to the far side of the transfer car 15 and hence will not strike the spring —39— until the wheels of the transfer car have left the bridging members, passes from the inclined surface of the spring, it comes in contact with the pin or stop —46— set up-right in the horizontal arm —41— and by 20 striking this arm turns the bridging member around its pivot until it is folded along the side of the car —R—. The spring —39— being below the level of the bridging 25 member does not interfere with this turning movement. The car —T— being locked within the car —R— continually keeps the members —35— folded in, but when the car —T— begins to move out of car —R— the 30 bar —44— releases the pin —46— the spring —38— extends the member, and the spring catch —39— locks the bridging member in its extended position, where it remains until the car —T— has passed on to 35 the platform and a new car —T— been brought into the car —R—.

The car —T— is provided with pneumatic bumpers —110— which lessen the shock of the same against the wall of car 40 —R—.

The mechanism for actually drawing the car —T— into car —R— and for pushing it out will now be described.

The transfer car is actually pulled aboard 45 the train by a pair of lazy tongs —47— guided between pairs of grooved rails —48 and 49— at the two ends of the reception car. The rear ends of the tongs are fastened to the crossed members —50 and 51— pivotally connected together at the center and in reality constituting a pair of scissors, synchronizing the movements of the lazy tongs. To the lower ends of these members —50 and 51— are pivoted the upright pitmen 55 —52 and 53— respectively which are connected with the tongs operating mechanism below the floor of the car.

A pin projects out horizontally on both 60 sides of the tongs at the central pivotal points of the tong members and rollers —54— are mounted on the ends thereof, the rollers being adapted to be guided in slots in the members —48— and 49. The rollers —54— increase in size from the rear to the 65 front end and at the limit of their forward

movement, downwardly and forwardly inclined slots —56— are formed in the guide-ways —48 and 49— so as to receive the rollers and to stop the forward movement of the tongs.

Each of the lazy tongs has two end levers —57— which are curved and overlap at their outer ends to form a ring when the lazy tongs are extended. These rings are adapted to engage hooks —58— on the ends 70 of the transfer car when car —R— comes opposite car —T— as the train passes the platform and to be operated by the mechanism beneath the floor of the reception car to draw the transfer car into the reception 75 car.

The hooks —58— are provided with shanks —59— extending along the sides of the car —T— and passing through the tubular supporting brackets —60—. The shanks slide 80 freely through the brackets —60— and normally hold hooks —58— extended from the sides of the car, being actuated by the coiled springs —61— through pinions —62— and racks —63— upon shanks —59. When the 85 hook is pushed in, as it is when the car —T— is placed within the car —R— and the hooks bear against the side of car —R— the coil springs —61— are wound up and when the car —T— is back on the platform, the 90 springs —61— extend them again. Coacting stops —64 and 65— on the shank and car —T— respectively, serve to prevent the hooks from being extended too far. The right hook (Fig. 1) extends farther from 95 the car —T— than the left hook and the rings of the tongs extend different distances from the car —R— in order that the right ring will engage only the right hook and the left ring will engage only the left hook. 100 The hooks are also at different elevations.

The tongs are operated, as before stated, by means of pitmen —52 and 53— pivotally connected to the crossed rods —50 and 51— at one end and are pivoted eccentrically to 110 crown gears —66— at the other ends. The rotation of these crown gears actuates the members —50 and 51— to extend and withdraw the tongs. Meshing with crown gears —66— are pinions —67— mounted upon sleeves —68— rotatively secured upon the ends of long shafts —69— but freely rotatable thereon.

Upon the other ends of shafts —69— are bevel gears —70— which in turn mesh with 115 the large horizontally disposed crown gear —71—. The brackets supporting the various shafts and gears have been omitted in some of the drawings to promote clearness.

Intermediate the ends of shafts —69— are bevel gears —72— meshing with bevel gears —73— which are rigid upon threaded shafts —74— projecting upwardly through the floor of the car and passing through 120 threaded openings in the ends of the two 125

end channel members 29. The rotation of shafts 69 through these gears raises or lowers the rear ends of the channels to tip them about their pivots. Sleeves 68 are provided on their inner ends with clutch teeth 75 adapted to coöperate with clutch teeth 76 on sliding sleeves 77. The sleeves 77 are splined to the shafts 69 and when the teeth 75 and 76 are brought into engagement, the sleeves 68 and pinions 67 are operated and the tongs extended or retracted.

In the operation of the mechanism it is desirable that the channel members be tipped up and the car T resting thereon be ready to pass down the incline onto the platform before the car is shoved out, to lessen the strain on the tongs which would otherwise be very great. For this reason, the clutch and sleeve members are used, as they enable the car to be tilted up and placed upon an incline before the tongs are operated.

To make the action automatic, I provide forked levers 78 pivotally secured to the side of car R and connected with the channel members in such a way that the clutches, and therefore the tongs are operated only after the channels have been tipped a considerable amount. This connection comprises two pulleys 79 and a belt 80 thereon provided with stops 81 which alternately engage the upper end of lever 78 to operate the clutch. Around pulleys 79 and with their ends secured thereto, are wires or cords 82 which extend upwardly and are attached to the channel members. When the channel members are tipped, cords 82 unwinding from spools 79 will rotate the same to cause clutch teeth 75 and 76 to engage each other. Springs 83 return belts 80 and hence levers 78 to their normal position (with clutches disengaged) when the channels are tipped downwardly to a horizontal position.

The means for actuating the gear 71 will now be explained. Meshing with the teeth of crown gear 71 is a pinion 84 mounted upon the end of a short horizontal shaft 85 which has mounted upon its other end the large vertical gear wheel 86. The shaft 85 together with pinion 84 and gear 86 may be raised or lowered, the shaft being journaled in a horizontal lever 87 pivoted to the car body near its middle point.

The gear wheel 86 is adapted to mesh with a rack 88 placed alongside the track opposite the platform 10 and to be rotated thereby, due to the motion of the train, to rotate the gear 71 and the other shafts and gears to operate the tongs. When the lever 87 has its right end raised 65 (Fig. 6), the gear 84 will not mesh with

rack 88 and the station will be passed by without discharging a transfer car. When the lever lets the gear 84 down, it will mesh with rack 88 and the transfer car will be discharged.

At the left of the pivotal point of the lever is a heavy weight 89 which normally tends to keep this end down and the gear 84 from reaching the rack. The right end of the lever is upturned and is adapted to enter between the lower ends of two heavy blocks 90 pivoted at their upper ends to a single pivot. Normally the blocks hang close together and the upturned end of the lever can not pass between them, but means are provided for opening the jaws at the proper time. This means comprises a lever 91 pivoted to a bracket secured to the car R below the blocks 90 and having a pin and slot connection with one of them. When the lower end of the lever strikes a block placed for that purpose along the track, it swings backwardly throwing the block to which it is connected at its upper end forwardly and allowing the end of the lever to pass upwardly therebetween to raise gear 84. By means of a pin and slot connection with the body of the car R the second block has a limited rotary motion so that it may fit tightly against the block, but retains its position when the latter is swung by the lever.

A push rod 92 is pivoted to the lever and extends upwardly to some point where it may be conveniently reached, as, for instance, the top of the car, and this is adapted to be used to push the lever 87 down so that the gears on shaft 85 mesh with rack 88 and gear 71 respectively. After being pushed down in this manner, blocks 90 come together and prevent the lever from rising. In passing a station with the operating parts in this position, a transfer car will be discharged, and after the platform has been passed the lower end of lever 91 strikes a block or trip 93 along the track and the blocks 90 are separated to allow the lever to rise and place gear 86 and pinion 84 in inoperative position, where they will remain until the push rod 92 is operated again.

The rack 88 is placed on the right of the track and opposite that part of the platform on which the car T is to be placed. As the gear 86 is heavy and also the chain of mechanism connecting it with the lazy tongs, it is desirable that means be provided for gradually starting it to turn before it strikes the rack 88 lest because of its inertia it break the teeth of the gear and rack.

This means comprises a series of comparatively light gears 94 mounted upon a support 95 in line with the rack 88. These gears are arranged so that they mesh 130

with the gear —86— as it passes above them and are close together so that they present an almost continuous toothed surface to the gear —86.

5 The first of these gears which the gear —86— strikes is freely rotatable, while the others are retarded by spring-pressed friction blocks —96— the friction applied being greater as the rack is neared. When the 10 gear —86— strikes the first gear, which rotates freely, it spins the latter and starts rotating in a reverse direction very slowly; the second gear will not spin so freely, and for this reason, the larger gear is accelerated 15 in its own rotation, and so on, until the rack —88— is reached. If the friction blocks —96— are properly adjusted, the circumference of the gear —86— will be traveling nearly as fast as the train, and 20 when the rack is reached no breaking of teeth will result. Of course, the rotation of the gear —86— actuates the mechanism connected thereto, but the tongs will not be operated before the rack is reached, the initial 25 rotation of the gear serving only to tip the channel members.

Pivoted to the side of the car —R— is a lever —97— which extends upwardly above the floor of the car and has its upper end 30 bent inwardly and upwardly to form a trip or catch. The downwardly projecting bracket —98— on car —T— strikes the inclined upper surface of this lever when car —T— is almost completely within car —R— 35 and depresses the same. After bracket —98— has passed over the catch, the weight of the lower end of the lever swings the catch back of bracket —98— and car —T— is locked in position. A block —99— placed 40 beside the track, tips the lever to release the car —T— at the proper time. In Fig. 6, the full line position of lever —97— shows the lever tipped in this way, and the car unlatched. Locking lever —97— is thrown 45 forward so as to be completely above the tripping block —99— when it is not desired to put off car —T— at any station. Between stations, it is also in this position and is held by the curved end of lever —87— 50 bearing against the inclined block —100— on lever —97—. When lever —87— is in the position shown in Fig. 6, the curved end is behind the pivotal point of lever —97— which is free to swing when it strikes the 55 block. When the lever —87— tips upwardly, the lower end of the lever —97— is elevated and the two objects are achieved at one time.

The means for bringing another car —T— 60 on to the car —R— at the other end of the platform are the same as used in putting it off, but operated in a reverse manner. A rack —102— on the left side of the train engages the large gear —101— which is 65 similar to gear —86— and motion of rota-

tion is transmitted to gear —71— in the reverse direction, through short shaft —103— pinion —104— horizontal crown gear —105— and small horizontal gear 70 106— meshing with 71. By this means the lazy 75 tongs are actuated to draw car —T— on to car —R— in a manner exactly the reverse of that in which it was put off.

Obviously the racks alongside the tracks must be carefully positioned so that the 75 tongs operate at the proper time.

In thrusting the car —T— on to the platform, the tongs, which have completely opened on contraction, do not grip the hooks as they do when the hooks are engaged to 80 draw the car from the platform, but pass completely around the hook so as to engage the rearwardly extending shanks —107— and 108— thereof. This allows the tongs to slip off of the hooks when the car —T— is 85 slowed up by the gears. A spring —109— holds the tongs fast on the hooks until the gears are reached by car —T.

After disengaging the racks —88— and 102— the wheels —86 and 101— will tend 90 to continue to rotate, due to their inertia, and as a means for bringing the two wheels and the connecting apparatus to a stop at the proper point, I provide raised friction faces —111 and 112— on wheels —86 and 95 105— respectively adapted to engage similar raised surfaces —113 and 114— respectively secured on the body of car —R—. Also I leave a gap in the peripheral teeth of gear —105— which gap is normally opposite the gear —106. This prevents the gear —71— from rotating gears —101 and 105— 100 while it does not prevent gear —105— from rotating gear —71.

The above described construction may be 105 modified for practical reasons, and I do not wish to confine myself to the exact apparatus shown.

What I claim is:

1. In a transfer system of the class described, a car adapted to be transferred to a vehicle moving along a trackway, means beside the trackway and actuated by said vehicle for accelerating said car, and means on the vehicle for transferring said car to 110 the vehicle.

2. In a transfer system of the class described, a car adapted to be transferred to a vehicle moving along a trackway, means beside the trackway for accelerating said 120 car, and means on the vehicle for transferring said car to the vehicle.

3. In a transfer system of the class described, a car adapted to be transferred from a trackway to a moving vehicle, means 125 extending from the path of said vehicle to said car and adapted to accelerate said car, devices on the vehicle for actuating said accelerating means, and means on the vehicle for transferring said car to the vehicle. 130

4. In a transfer system of the class described, a car adapted to be transferred to a vehicle moving along a trackway, a series of gears on stationary shafts actuated by said vehicle for accelerating said car, and means on the vehicle for transferring said car to the vehicle.
5. In a transfer system of the class described, a car adapted to run along a trackway and to be transferred from the trackway to a moving vehicle, a series of gears under said trackway, a rack beneath said car adapted to engage said gears successively, means coöperating with said vehicle to actuate said gears and to accelerate said car, and means on said vehicle for transferring said car to said vehicle.
6. In a transfer system of the class described, a car adapted to run along a trackway and to be transferred from the trackway to a moving vehicle, a series of vertically disposed gears between the rails of said trackway, a rack beneath said car adapted to engage said gears successively as the car passes along the trackway, means actuated by a passing vehicle for rotating said gears in the same direction, but at successively higher speeds from the center toward each end of the trackway, whereby the car is accelerated as it passes from the center to one end of the trackway and retarded as it passes from the other end of the trackway toward the center, and means on said vehicle for transferring said car to said vehicle.
7. In a transfer system of the class described, a car adapted to run along a trackway and to be transferred from the trackway to a moving vehicle, a longitudinal shaft beneath said trackway, a series of gears mounted thereon, a series of short transverse shafts beneath said trackway, gears on said transverse shafts meshing with the gears of said longitudinal shaft, said intermeshing gears varying progressively in size from the middle of the trackway toward the ends thereof, vertically disposed gears also on said transverse shafts and extending upwardly between the rails of said trackway, a rack on said car adapted to successively engage said vertically disposed gears as it passes along the trackway, means connected with said longitudinal shaft adapted to be actuated by a passing vehicle to rotate said shaft and said transverse shafts and gears whereby said car is moved along said trackway, its motion being accelerated as it leaves the middle of the trackway and approaches the end thereof, or retarded as it leaves the other end and approaches the middle, and means on said vehicle for transferring said car to said vehicle from said trackway and for transferring said car from said vehicle to said trackway.
8. In a transfer device of the class described, two parallel trackways, a transfer car adapted to run on one of said trackways, a train on the other of said trackways, a reception car in said train adapted to receive and contain the transfer car, a rack on said train, a gear between said trackways and adapted to be rotated by the rack on said train as the train passes the same, means connected with said gear and operated thereby for accelerating said car when the gear is rotated by the passing train, and means for transferring said transfer car from said trackway to said reception car.
9. In a transfer device of the class described, two parallel trackways, a train upon one of said trackways, a reception car in said train, a transfer car upon the other of said trackways, means adapted to be actuated by the train for accelerating said transfer car to the speed of the train, bridging members pivotally secured to said reception car and adapted to be extended toward the other trackway, and means on said reception car for engaging said transfer car and drawing the same over said bridging members into said reception car.
10. In a transfer device of the class described, two parallel trackways, a train upon one of said trackways, a reception car in said train, a transfer car in said reception car, a transfer car upon the second of said trackways, and means for transferring the first mentioned transfer car to said trackway, and for transferring the last mentioned transfer car to said reception car, said means comprising bridging members pivotally secured to said reception car, and extending toward said trackway, means for moving said first mentioned transfer car over said bridging members to said second trackway, means for drawing said last mentioned transfer car over said bridging members into said reception car, and means actuated by said train for retarding and stopping said first mentioned transfer car and for accelerating said last mentioned transfer car to the speed of the train.
11. In a transfer device of the class described, a platform, a trackway adjacent said platform, a vehicle on said trackway adapted to contain a transfer car, a transfer car, means for transferring said transfer car from said platform to said vehicle when the vehicle is in motion, and automatic locking means on said vehicle for holding said transfer car within the vehicle after the transfer.
12. In a transfer device of the class described, a platform, a trackway adjacent said platform, a vehicle on said trackway, adapted to contain a transfer car, a transfer car, means for transferring said transfer car from said vehicle to said platform when the vehicle passes the platform, means

mounted adjacent said trackway for engaging said means and operating the same due to the motion of the vehicle, and manually operable means for controlling the transferring means whereby it may be prevented from operating to transfer the car.

13. In a transfer device of the class described, a platform, a trackway adjacent said platform, a vehicle on said trackway 10 adapted to contain a transfer car, bridging members secured to said vehicle and extending toward said platform, a transfer car in said vehicle, a cog wheel secured to said vehicle, a stationary rack beside said platform, adapted to be engaged by said cog wheel when the vehicle passes the platform, and means connected with said cog wheel for transferring said transfer car from said ve-

hicle to said platform when said cog wheel engages said rack.

14. In a transfer device of the class described, a platform, a trackway beside said platform, a transfer car on said platform, a vehicle on said trackway, a second transfer car within said vehicle, means for transferring said second car to said platform and for drawing said first mentioned car into said vehicle as the vehicle passes the platform, and retarding and accelerating means actuated by the passing vehicle for stopping the second car upon the platform and for accelerating said first car to the speed of the train.

In testimony whereof I affix my signature.

WILLIAM P. LAMAR.
